UNITED STATES PATENT OFFICE.

SAMUEL SUEKOFF, OF CHICAGO, ILLINOIS.

SPRING CUSHION CONSTRUCTION.

Application filed June 16, 1924. Serial No. 720,161.

To all whom it may concern:

Be it known that I, SAMUEL SUEKOFF, a citizen of the United States of America, and a resident of Chicago, Cook County, Illinois, have invented a certain new and useful Improvement in Spring Cushion Constructions, of which the following is a specification.

This invention relates to improvements in spring cushion construction and method of manufacturing the same and more especially to self-contained spring assemblies for upholstered seat cushions, furniture, motor cars and the like.

The object of the invention is to provide an improved method of fastening and sewing together the pieces of fabric that make up the outer covering and inner compartments or cells into which the springs are inserted, the purpose being to provide ample strength, shape retaining qualities, ease and rapidity in the sewing operations, and ready insertion of the springs into the cover.

A preferred embodiment of the invention is illustrated in the accompanying drawings, in which:

Figure 1 is a top plan view of a cushion with a portion of the fabric removed to show the internal structure,

Figure 2 is an enlarged view in vertical section taken longitudinally or lengthwise of the spring compartments on line 2—2 of Figure 1.

Figure 3 is an enlarged view in vertical section taken transversely of the spring compartments as on line 3—3 of Figure 1.

Figure 4 is an enlarged detail view in perspective showing the partition stubs sewed to the bottom cover piece, and

Figure 5 is a perspective view of a single spring retaining member before sewed to the cover pieces.

A cushion of the type embodying the features of the invention consists of a casing of burlap fabric made up of pieces cut to size and sewn together on machines. Within this casing is a multitude of coil springs arranged in rows, each spring being separated from its neighbor by surrounding walls of fabric, so arranged as to form individual cells for each spring. The cushion may be of any shape, size and thickness, the one herein disclosed being square.

Considering the cushion as a completed article of manufacture, the same comprises a top cover piece 1 and a bottom cover piece

2, the two being designated for the purpose of this description only. These cover pieces are of equal size and square in shape, being cut to larger dimensions than the finished cushion since the margins of each are folded at right angles and their edges brought together and stitched around the sides and ends at 3, thereby forming the boxing or side walls 4 and end walls 5.

The interior of the cushion is divided into spring compartments for the individual springs 6. The space is divided into longitudinal compartments extending the length of the cushion by means of a plurality of partition walls 7, made of strips of burlap, stitched along their edges to the top and bottom pieces and extending vertically or at right angles therebetween. These partition walls 7 are spaced apart at equal distances from side to side, dividing the space into six (Figure 1) of these full length compartments.

Dividing each of the lengthwise compartments into an equal number of small square compartments is a series of division walls 8, spaced apart at equal intervals and extending transversely between the partition walls 7. The width of the division walls 8 is less than the distance between the partition walls 7 so that a space separates the edges of the former from the latter, as clearly shown in Figure 3.

These division walls are not separate pieces but form a series of tabs which are sewn to and form a part of a unitary member, consisting of a plurality of such tabs sewn to a long narrow strip 9, the complete member being shown in Figure 5. This member, when in place, extends lengthwise between the partition walls 7, the lower ends of the division walls or tabs being stitched to the bottom piece 2, as shown in Figures 1 and 3, and the narrow connecting strip stitched to the top piece along one edge only, the lines of stitching being indicated by 10 in Figure 1, and as it will be observed, extend parallel to and adjacent the lines of stitching 11, of the partition walls 7. Thus it is seen that the division walls or tabs 8 are not sewed directly at both ends to the top and bottom pieces, but only at one end, the opposite ends being sewn to the connecting strip 9, which in turn is stitched to the top piece 1. In this manner one edge of the connecting strip is free and partakes of the nature of a flap, the purpose of which will

hereinafter be disclosed. The connecting strip 9 is furthermore extended at its ends beyond the length of the cushion, in the form of end sections 9^a, 9^b, which are carried down halfway of the end wall boxing and their extreme edges included in the hem made by sewing the edges of the top and bottom pieces together at 3. This is clearly shown in Figure 2.

10 Within these square compartments is inserted a spring 6, the same being separated by the vertical walls on four sides. The method of assembling the material to make the cushion involves a series of sewing operations which must be carried out in a prescribed order since otherwise it would be impossible to use sewing machines.

Hence, it is necessary to sew the free ends of the tabs 8 to the bottom piece as the first 20 operation. Thus, beginning at one end of a bottom piece, all of the first or end most row of tabs 8 of the several connected tab members, are sewn down by a single operation, then the second row, and so on until 25 all are secured to the same cover piece. Next, the partition walls are stitched down to the same piece and between the rows of tabs 8, thereby completing one half of the cover. Next, the other (top) cover piece is 30 applied, and one edge of each connecting strip 9 and the edges of the partition walls are sewed to the top piece. The ends and sides are then closed and the boxing formed by sewing around the outside along the line 35 3, one end being left open for the insertion of the springs, this operation being termed loading.

The loading of the cushion is carried out 40 by means of a loading fixture, which in its simplest form are two thin wood or metal strips between which are compressed a row of springs of the number and spacing required to fill a single row of cells within each longitudinal compartment. When 45 compressed, the strips are clamped together and inserted endwise into the open end of the compartment. In doing this, the fixture is inserted between the top piece 1 and the connecting strip or flap 9, so that it does 50 not encounter the division walls or tabs 8. When the fixture is inserted its full length, the same is twisted axially toward and over the free edge of the flap, a half turn which brings each spring into its respective compartment with the flap beneath one end. By 55 releasing the fixture, the springs expand and spring into their final positions, whereupon the fixture is withdrawn and the next row loaded. When the loading is completed 60 the open end is sewed up and the cushion is complete.

The advantage of this particular construction, the rapidity and ease of loading 65 is greatly increased, in that the cushion can be completely sewed up for loading, and

then by the use of a fixture the gang method of loading can be employed, which would be impossible were the edges of the division tabs sewed directly to the top and bottom pieces, thus necessitating the use of the space 70 at the corners of each cell for introducing a spring therein, this being a slow and tedious and expensive operation.

Having set forth the important features of the cushion construction embodying the 75 invention, and explained the method of assembling and loading the cushion, I claim:

1. A method of constructing spring cushions consisting of providing a plurality of connecting strips, each having a series of 80 tabs stitched transversely thereof, stitching the free ends of said tabs to a cover piece in parallel rows, stitching one edge of each strip to another cover piece and sewing partition strips to said cover pieces and between the rows of tabs and connecting strips.

2. A method of constructing spring cushions consisting of providing a strip having a series of tabs stitched transversely 90 thereof, stitching the free ends of said tabs to a cover piece in predetermined order and arrangement, sewing partition walls to said cover piece, between the rows of tabs of each strip, providing another cover piece and stitching the free edge of said partition strips and said tab connecting strip to said last mentioned cover piece.

3. A method of constructing spring cushions consisting of providing separate 100 cover pieces, providing a plurality of relatively narrow connecting strips having a series of tabs sewed transversely thereof and at equal distances apart, sewing the free end of one of the endmost tabs of each strip in 105 spaced relation along a line parallel to the end edge of one of said cover pieces, sewing the next series of tabs and so on until all are secured to the same cover piece, stitching a series of partition strips to said cover piece, and along parallel lines between said series of tabs, applying another cover piece, and securing one edge of said connecting strip and the free edges of said partition strips to 110 said last mentioned cover piece.

4. A method of constructing spring cushions consisting of providing separate 120 cover pieces, providing a plurality of relatively narrow connecting strips having a series of tabs sewed transversely thereof and at equal distances apart, sewing the free end of one of the endmost tabs of each strip in spaced relation along a line parallel to the end edge of one of said cover pieces, sewing the next series of tabs and so on until all are secured to the same cover piece, stitching a series of partition strips to said 125 cover piece, and along parallel lines between said series of tabs, applying another cover piece, sewing one longitudinal edge of said 130

connecting strip and the free edges of said partition strips to said last mentioned cover piece, sewing the margins of said cover pieces together around the sides and one end 5 of the cushion to form the boxing, one end of said connecting strip being sewed with the end margins of the cover pieces, and loading the compartments formed by the partition strips, from the open end of the

cushion by inserting a loaded fixture between the connecting strip and the adjacent cover piece, rotating the fixture to bring the springs into the individual spring compartments, and releasing the springs from the fixture. ¹⁰

Signed at Chicago, this 12th day of June 1924.

SAMUEL SUEKOFF.
